DESIGN.

H. A. LEE.
SALT BRICK HOLDER.

No. 28,151

Patented Jan. 11, 1898.

UNITED STATES PATENT OFFICE.

HENRY A. LEE, OF BROOKLYN, NEW YORK.

DESIGN FOR A SALT-BRICK HOLDER.

SPECIFICATION forming part of Design No. 28,151, dated January 11, 1898.

Application filed November 16, 1897. Serial No. 658,763. Term of patent 14 years.

To all whom it may concern:

Be it known that I, HENRY A. LEE, a citizen of the United States, residing at Brooklyn, in the county of Kings and State of New York, have invented and produced a new and original Design for a Salt-Brick Holder, of which the following is a specification.

The leading feature of my design consists of an open three-sided frame, with the vertical sides inclined toward each other from the back to the front and a bottom with a backwardly-curved front edge and curved lugs in the same plane at the back.

This design for a salt-brick holder is shown in the accompanying drawings, wherein—

Figure 1 is an elevation, and Fig. 2 is a plan view.

The vertical sides A A' are at an inclination toward each other, and the bottom B is nearly level and has a backwardly-curved edge, and the rounding flanges at C D E are in the same plane. 20

I claim—

The design of the salt-brick holder as described and shown. 25

Signed by me this 15th day of November, 1897.

HENRY A. LEE.
